UNITED STATES PATENT OFFICE.

JAMES WILSON, OF ST. LOUIS, MISSOURI.

DESIGN FOR A HEATING-STOVE.

SPECIFICATION forming part of Design No. 24,242, dated April 23, 1895.

Application filed October 29, 1894. Serial No. 527,352. Term of patent 7 years.

To all whom it may concern:

Be it known that I, JAMES WILSON, of the city of St. Louis, State of Missouri, have invented a new and original Design for Heating-Stoves, of which the following is a full, clear, and exact description, reference being had to the accompanying drawings, forming a part hereof.

In the drawings, Figure 1 is a side elevation of a stove embodying my design. Fig. 2 is a top plan view thereof.

The leading feature of my design consists in an elongated inverted conical body located exterior of an oval body and extending substantially parallel therewith from a point adjacent the base of said oval body to a point in a plane adjacent the top thereof.

1 indicates the oval body provided with parallel corrugated belts or bands 2 located one belt or band adjacent the top, and another belt or band adjacent the bottom of said oval

body. Extending upward from the top and near one end of the body 1 is a truncated cone 3 surmounted by a fanciful or ornamental smaller body 4. An elongated inverted conical body 5 is located exterior of said oval body 1 at one end of the latter and extends from a point adjacent the base thereof to a point in a plane adjacent the top of said oval body. The conical body 5 is surmounted by a cap 6 from the center of which rises an ornamental spherical body 7.

What I claim is—

The design for a heating stove, as herein shown and described.

In testimony whereof I affix my signature in presence of two witnesses.

JAMES WILSON.

Witnesses:

E. E. LONGAN,
JNO. C. HIGDON.
